UNITED STATES PATENT OFFICE.

JESSE G. HILTON, OF MENA, ARKANSAS.

OIL-BURNER.

1,070,469.

Specification of Letters Patent. Patented Aug. 19, 1913.

Application filed October 29, 1912. Serial No. 728,366.

To all whom it may concern:

Be it known that I, JESSE G. HILTON, a citizen of the United States, and a resident of Mena, in the county of Polk and State of Arkansas, have invented certain new and useful Improvements in Oil-Burners, of which the following is a specification, reference being had to the accompanying drawings.

10 This invention relates to oil burners of that class arranged to be placed in the fire box of a cooking or heating stove, and comprises a housing having two extending burner tubes, each provided with a plurality 15 of gas ports arranged so as to insure perfect vaporizing and complete combustion. The burner further is of a simple and inexpensive nature and of a compact and durable construction.

20 The present invention is a structural improvement in oil burners, the housing or generator chambers are so arranged to give perfect vaporization and under the pressure used in the oil tank the vaporized oil will 25 mix with the oxygen of the air while passing from the burner to the generator. Hence the space between the burner and the generator has to be some distance for said effect.

30 With these and other objects in view, the present invention consists in the combination and arrangement of parts as will be hereinafter more fully described and finally 35 pointed out in the appended claim, it being further understood that changes in the specific structure shown and described may be made within the scope of the claim without departing from the spirit of the invention.

40 In the accompanying drawings forming a part of this specification and in which like numerals of reference indicate similar parts in the several views: Figure 1, shows a central sectional view of an improved oil burner 45 embodying my invention. Fig. 2, is a bottom view of Fig. 1.

In carrying out the aim of my invention, I employ an oil burner including a housing 10, having the intake chamber 11, which at 50 one end has the threaded inlet port 9. This intake chamber near the opposite end has the exit port 15, which leads centrally into the generating chamber 12. This chamber

at each end communicates with the adjacent generating chambers 13. The wall 8 divides one chamber from the other. As shown each chamber has a threaded escape port 16. Threaded into these ports 16 are the nipples 17, from which extend the elbows 18, and held to each elbow 18 is a burner tube 19, each tube having two gas ports 21, which, as indicated by arrows, are directed toward the housing. The burner tubes 19 are closed by means of the caps 20.

Entering the threaded port 9, is the nipple 22 provided with the valve 23, into which is led the oil supply pipe 24.

From the foregoing it will be readily seen that the fuel enters the burner through the nipple 22 first entering the chamber 11, from which the fuel escapes through the exit port 15, into the generating chamber 12. Here the fuel is thoroughly vaporized and escapes therefrom at each end into the lower generating chamber 13. From this chamber 13 the vapor escapes through the nipples and burner tubes 19, finding an outlet through the gas port 21. By this means as the housing is directly over the flame the oil will be quickly vaporized, insuring a complete combustion of the gases.

In order to enable the housing being cleaned, I provide at one end the threaded opening 25, which communicates as shown with the generating chambers 12 and 13, so that these chambers may be cleaned. The plug 26 is removably held within the threaded opening 25.

A burner constructed according to my invention is simple and inexpensive and both durable and efficient in operation and can be arranged within the fire box of any conventionally constructed stove with ease, accuracy and despatch.

Having thus described my said invention what I claim as new and desire to secure by United States Letters Patent is:

An oil burner comprising a housing, said housing formed with an oil intake chamber, a generating chamber, an exit port leading from the intake chamber centrally into the generating chamber, other generating chambers adjacent said first mentioned generating chamber, means for communicating said last mentioned generating chambers with said first mentioned generating chamber,

one last mentioned chamber communicating with each end of said first mentioned chamber, said last mentioned chambers each having an escape port located centrally of the 5 burner, a valve controlled oil inlet entering said oil chamber, a nipple within each of said escape ports, and a burner tube extending from each nipple, each burner tube hav-

ing a plurality of gas ports, as and for the purpose set forth.

In testimony whereof I affix my signature, in presence of two witnesses.

JESSE G. HILTON.
